UNITED STATES PATENT OFFICE.

GEORGE W. LEE, OF MUNCIE, INDIANA.

EVAPORATING APPARATUS.

SPECIFICATION forming part of Letters Patent No. 415,541, dated November 19, 1889.

Application filed May 21, 1889. Serial No. 311,578. (No model.)

To all whom it may concern:

Be it known that I, GEORGE W. LEE, a citizen of the United States, residing at Muncie, in the county of Delaware and State of Indiana, have invented certain new and useful Improvements in Evaporating Apparatus; and I do hereby declare the following to be a full, clear, and exact description of the invention, such as will enable others skilled in the art to which it appertains to make and use the same.

My invention relates to improvements in apparatus for evaporating or concentrating liquids or solutions; and it consists in certain novelty in the construction, arrangement, and combination of the various parts, all of which I will now proceed to point out and describe, reference being had to the accompanying drawings, in which—

Figure 1 is a perspective view of my said invention; Fig. 2, a perspective view of the supports for the evaporating apparatus, said apparatus being removed; Fig. 3, a side elevation of the evaporating apparatus removed from its bearings; and Figs. 4, 5, 6, and 7 are details of various parts of my said invention.

Referring to said drawings, A A' represent suitable supports or bases having a space between the same, and on which the evaporating apparatus is mounted, as hereinafter described. Said supports are preferably constructed of masonry, but may be made of wood or metal, if so desired.

On top of the base or support A, I secure a casting B, and on the support A' a casting B'. Said castings are similar in construction, and on each are formed bearings b b, in which are mounted grooved rollers b' b', said rollers forming roller-bearings, for a purpose herein-after set forth.

C is an arm or bracket secured to one side of the support A' and having formed therein a bearing c.

b² is a bearing secured upon the support a'. D is a shaft mounted in said bearings c and b². d is a pinion mounted on the inner end of said shaft and located between the rollers b'. On the outer end of this shaft is mounted a pulley D', which has belt-connection with suitable driving mechanism, which in the present instance is not shown. Any desired power may be used.

E E' are hollow cylindrical chambers mounted on the supports. The chamber E is provided with a central annular flange e, 55 which engages with the rollers b' on the base A, and the chamber E' is provided with a similar annular flange e', which engages with the rollers b' on the support or base A'. For convenience in construction said flanges are 60 preferably formed of cast-metal bands bolted or riveted to the chambers, and may, if desired, be made in two parts. The flange e' is provided at its center with gear-teeth, which form a gear e², with which the pinion d engages. To the outer end of each of the cylindrical chambers is riveted or otherwise secured bands F, having an annular flange f. To said flanges are secured heads F' F', provided with hinged doors F², having steam-tight connections with said heads.

To the inner end of each chamber is riveted or otherwise secured a similarly-formed band G, having an annular flange g, to which is secured a head G', having perforations g' therein. To the center of each head G' is attached a casting g², to which is secured one end of a rod G³, which forms a rigid connection between the two chambers.

H are hollow tubes or pipes having their 80 ends secured in the perforations in the heads and forming a connection between the hollow chambers, said tubes being so attached to the heads that steam-tight joints are made. In the center of the doors F² are stuffing-boxes I.

K is an induction steam-pipe, which enters the chamber E through its stuffing-box I, said pipe being connected with a suitable source of supply and provided with a valve k. 90

L is an exhaust or escape pipe, having its inner end entering the chamber E' through its stuffing-box I. Said pipe is supported in the upper end of the arm or bracket C and may be arranged to exhaust into a vessel L'. 95 When the steam is turned on, it passes into the chamber E', and from said chamber through the hollow tubes H into the chamber E and out through the exhaust or escape pipe L, the induction and exhaust pipes being arranged to permit the chambers to revolve. Said chambers being rigidly connected, when the shaft D is rotated its pinion d, engaging with the gear e², rotates both of

the chambers and the interposed and connecting pipes. It is apparent that hot air or water may be used with this mechanism. I however prefer to use steam.

5 Located over the tubes H is a distributing pan or vessel M, having one side n cut away, said cut-away side being about over the center of the revolving tubes.

N indicates a pipe leading from a reservoir 10 or other source of supply which contains the liquid or solution to be evaporated. Said pipe discharges into the vessel M, and as said vessel fills it overflows on its cut-away side, the liquid or solution falling upon and passing 15 between and over the revolving heated tubes, which present a large heating-surface and cause said liquid to be rapidly evaporated. The residuum or concentrated liquid falls into a receiving-pan O, which is placed under the 20 tubes H. If desired, said receiving-pan may be permanently fixed and emptied from time to time, as becomes necessary. It is, however, more convenient to have a removable pan, as shown.

25 From the above description the operation of my said invention will be readily appreciated. It is apparent that it may be used for a variety of purposes. It is, however, especially adapted to be used with chemical 30 apparatus employed to evaporate various solutions.

Having thus fully described my said invention, what I claim as new, and desire to secure by Letters Patent, is—

35 1. In an apparatus for evaporating liquids, the combination, with suitable supports having grooved rollers mounted thereon and two

rotatable hollow chambers mounted upon the rollers and having annular flanges engaging with the grooves in said rollers, of independent tubes interposed between and connecting the interiors of said chambers, an induction-heat-supply pipe communicating with one chamber, an exhaust-pipe leading from the other chamber, mechanism for rotating said 45 chambers and interposed connecting-tubes, and a distributing-vessel arranged to discharge upon said tubes, all constructed, arranged, and operating substantially as shown and described.

2. In an apparatus for evaporating liquids, the combination, with the grooved rollers mounted upon suitable supports A A', the shaft D, carrying the pinion d and mounted upon the support A' of the hollow chamber E, 55 provided with the annular flange e, engaging with the rollers b' on the support A, the hollow chamber E', having the annular flange e', engaging with the grooved rollers b' on the support A' and provided with the gear e², 60 with which the pinion d engages, the tubes H, rigidly secured to and connecting the interiors of said chambers E E', and over which tubes the liquid to be evaporated is adapted to flow, all constructed, arranged, and operating substantially as shown and described, 65 and for the purpose set forth.

In testimony whereof I affix my signature in presence of two witnesses.

GEORGE W. LEE.

Witnesses:

ADDIE HATHAWAY,
L. SCHAEFFER.
